UNITED STATES PATENT OFFICE

STUART DEAN, OF INDIANAPOLIS, INDIANA, ASSIGNOR TO DEAN BROTHERS COMPANY,
OF INDIANAPOLIS, INDIANA. A CORPORATION

PUMP MECHANISM

Application filed September 16, 1927. Serial No. 219,868.

This invention relates to a pump mechanism, particularly the actuating mechanism including the lubricating system therefor and the connection therebetween.

One object of the invention is to provide a power head for a duplex pump which is self-lubricating.

Another object of the invention is to provide in a power head for a duplex pump a novel power mechanism which approximates the quartering drive heretofore employed in duplex pumps.

One feature consists in the provision of means for preventing drip from the pump 15 entering the power head positioned therebelow.

Another feature of the invention consists in positioning the pump mechanism in superposed and spaced relation to the power mechanism and providing a detachable connection therebetween.

The full nature of the invention will be understood from the accompanying drawings and the following description and claim.

Fig. 1 is a side elevation of a duplex pump including the invention. Fig. 2 is an end elevation with parts broken away to show a conventional part of the pump mechanism. 30 Fig. 3 is a top plan view of the same with parts of the pump mechanism broken away and the cover of the oiling channel removed. Fig. 4 is a vertical sectional view taken on line 4—4 of Fig. 2. Fig. 5 is a sectional view 35 taken on line 5—5 of Fig. 4 and in the direction of the arrows with both piston rods in the same lowered position. Fig. 6 is a view similar to Fig. 5 with one of the piston rods in the uppermost position and the other in 40 the lowermost position. Fig. 7 is a transverse sectional view taken on line 7—7 of Fig. 3 in the direction of the arrows and illustrates the method of lubricating the several parts.

In the drawings 10 indicates a cubical box 45 or base which receives the power unit of the pump and said base includes the feet 11 or an anchoring flange, if desired. The upper portion of the box includes a flange 12 and the power head 13 includes a complementary flange 14 whereby the head and base are se-

cured together. A plurality of spacing standards 15 support the plate 16 of the duplex pump construction and maintains said pump construction in spaced relation to the power unit. The base 16 supports the cylinder block 17 including the cylinders 18 and the block also supports the head 19. Mounted in each cylinder is a piston 20 carried by a rod 21 which passes thru a stuffing box 22 carried by the plate 16. In actual construction, the piston rods are detachably connected to the power rods in aligned relation therewith and such detachable connection 121 is provided in the space between the plate 16 and the head 13. Also, to prevent any leakage of water from the pump portion of the mechanism to the power portion of the mechanism each of the piston rods 21 mounts a petticoat 23 which will throw the leaking water, if any, away from the rod 21 where it passes thru and into the power head 13 (controv. 50) (at notificd 70)

The pump is operated thru any suitable source of power and herein the head 13 supports a power shaft 24 which is shown provided with a power pulley 25 for actuation. Any other suitable drive may be provided. The shaft 24 is rotatably mounted in a pair of brackets 26 in the bearings 27 thereof. The brackets 26 include the wings 28 by which the same are anchored by the bolts 29 to the head 13. Each bracket 26, beneath the bearing 27, includes a bearing 30 and, extending in offset relation therewith, that is, downwardly and toward one side, is the extension 31 which terminates in a bearing 32. 5 lb of 8

The crank shaft 33 has the bearing portions 34 mounted in the bearings 30 of the brackets and one end 35 is extended and mounted thereon is a driving gear 36 which meshes with the pinion 27 carried by shaft 90 24, said shaft being mounted in bearings 27 as aforesaid, not being mounted short of said bearings.

Said bearings are lubricated as follows:

The pinion 37 takes oil from the gear 36 if the oil level is not as high as the lower most part of the pinion, which lower level generally is the case. The pinion 37 discharges the oil by centrifugal force against the wall 40 of the channel-forming portion of the head, which channel encloses the power

shaft 24, or directly thru the opening or slot 42 in the channel portion 41 and the casting is provided with an enclosing wall 43 which forms a trough or channel, the floor 44 of which is pitched so as to insure the flow of oil which has been thrown thru the slot 42 along the floor 44 to the openings 45, and said openings discharge thru the head of the chamber 41 into the recess 46 and the openings 47 permit the lubrication of shaft 24 in its bearings.

Each piston rod 21 includes a head 48 carrying wrist pin 49 and a multiple link 50 is united to the piston rod thereby. The other end of the link 50 is pivoted to a triangular plate 51 at 52 by pin 53. The pivot pins 53 are positioned at two of the vertices of the triangular casting 51. The other vertex of the triangular casting 51 includes a bearing 54 which receives the crank or eccentric portion 33 of the crank shaft having the bearing portions 34. A pair of links 55 are pivotally supported at one end by pin 56 in the end 32 of the offset portion 31 of the brackets. The other end of the link 55 is pivotally connected at 57 to the triangular casting 51 by the pivot 58 which is substantially midway between the pivotal bearings 52 and in alignment with the crank shaft bearing 54.

The operation of the device is as follows: Rotation of the main power shaft 24 together with the gear rotates crank shaft 33 which actuates the triangular plate 51 and gives it a rocking motion. When the crank portion is in the lowermost position it is as shown in Fig. 5. If the crank shaft rotates counter-clockwise, the quarter position therefrom is as shown in Fig. 6. Then the next quarter position is as shown in Fig. 5 except that the crank portion 33 is positioned above the bearing portion 30 an equal amount and, therefore, the piston rods are positioned above an equal amount, the link 55 in this movement swinging thru an arc and taking a position substantially as indicated by the dotted line X. Continued rotation of the crank shaft will reverse the position of the triangular plate 51 from that shown in Fig. 6 to an oppositely tilted position and in this movement the end 52 of the plate 51 passes between the links 55 until positioned in approximately the same plane as the lowermost end 52 but on the opposite side.

The invention claimed is:

In a pump mechanism, a pair of vertically disposed piston rods mounted for parallel reciprocating movement, a pair of links each pivoted at one end to a piston rod, a crank shaft disposed midway between said rods, a triangular actuator pivotally connected at its upper vertex to said crank shaft, the lower vertices of said actuator being in true vertical alinement with said rods when the upper vertex is disposed midway between the

same, the said links pivoted one to each of said lower vertices, an anchoring link pivoted at one end to said actuator midway between said lower vertices and at its opposite end to a stationary support laterally beyond one of said links, and means for rotating said crank shaft.

In witness whereof, I have hereunto affixed my signature.
